(57) **CLAIM**

The ornamental design for a planter, as shown and described.

DESCRIPTION

FIG. 1 is a front-top-left side perspective view of a planter showing our new design;

FIG. 2 is a front view of the planter, a rear view being a mirror image of the front view;

FIG. 3 is a left side view of the planter, a right side view being a mirror image of the left side view;

FIG. 4 is a top view thereof;

FIG. 5 is a bottom view thereof;

FIG. 6 is a front-left side-bottom perspective view thereof; and,

FIG. 7 is a rear-right side-top perspective view thereof.

1 Claim, 7 Drawing Sheets(56)
